UNITED STATES PATENT OFFICE.

BURTON H. CLEMENT AND GEORGE A. CLEMENT, OF BELOIT, WISCONSIN.

SELF-CENTERING PUNCH.

SPECIFICATION forming part of Letters Patent No. 718,427, dated January 13, 1903.

Application filed February 28, 1902. Serial No. 96,055. (No model.)

To all whom it may concern:

Be it known that we, BURTON H. CLEMENT and GEORGE A. CLEMENT, citizens of the United States, residing at Beloit, county of Rock, and State of Wisconsin, have invented new and useful Improvements in Self-Centering Punches, of which the following is a specification.

Our invention relates to improvements in self-centering punches.

The object of our invention is to provide means whereby a set of jaws may be simultaneously actuated equally toward a common center in line with the central axis of the punch.

In the following description reference is had to the accompanying drawings, in which—

Figure 1 is a side view of our invention. Fig. 2 is a longitudinal sectional view of the same. Fig. 3 is a view of the lower end. Fig. 4 is a sectional view drawn on line $\alpha\alpha$ of Fig. 2. Fig. 5 is a detail side view of one of the jaws and jaw-supporting arms.

Like parts are identified by the same reference characters throughout the several views.

In the drawings, 1 is the punch. 2 is a tubular guide therefor, provided with circular disks or head-flanges 3 and 4 at or near its lower end.

5 represents centering-jaws which connect with an arm 6, which is pivoted at 7 between the head-flanges 3 and 4, the arm 6 and jaws 5 being in the form of a forked piece of metal, Fig. 5, with the jaw-arm of the fork bent, as best shown in Fig. 3, the jaws being so formed that when the arms 6 are folded into proximity with the adjacent pivots, as indicated by dotted lines in Fig. 3, the jaws 5 will meet in the center line of the punch 1, the jaws 40 being retracted from this position by swinging the arms 6 outwardly until such arms extend radially from the common center, as also shown in Fig. 3. In order to actuate all the jaws simultaneously and equally, we have provided a jaw-actuating ring 8, having diagonal open-ended guide-slots 9, through which the arms 6 of the jaws pass. When the ring 8 is moved in the direction indicated by the arrows in Fig. 3, the arms 6 of the jaws will be carried around to the folded position shown in dotted lines in said figure and the jaws brought into central contact, as above stated.

By rotating the ring in the opposite direction, however, the jaws are retracted until the arms 6 thereof are adjusted in radial lines. 55

Aspiral spring 15 is coiled around the guide 2 within the collar 8, one end of the spring being secured to the head-flange 4 and the other being secured to the collar, as best shown in Fig. 2, the spring being arranged to hold the jaws normally in closed position. The ring 8 is held in position by means of a sleeve 16, enlarged to form an annular bearing at 17 for the ring 8. The latter also has a bearing upon the head-flange 4. The sleeve 16 is secured to the guide 2 by a set-screw 18, which also engages in a channel or recess 19 in the punch 1, whereby the latter is permitted a limited movement, but is prevented from turning or dropping out of position. 70

In use the jaws are opened when rotating the ring 8 and sleeve 16 upon each other, both being milled or knurled to facilitate such manipulation, the ring being turned in the direction indicated by the arrows in Fig. 3 or 75 an equivalent movement being imparted to the sleeve 16 in the opposite direction, whereupon the jaws will be retracted to their open position. Work can then be inserted between the jaws, when on releasing the ring 8 the reaction of spring 15 operates to close the jaws upon the work, and as the jaws are all equally actuated toward a common center the work will be brought to an exact central position. A blow upon the punch 1 is then 85 administered, causing the point of the punch to dent the work exactly in the center.

Having thus described our invention, what we claim as new, and desire to secure by Letters Patent, is—

1. The combination with a punch; of a tubular guide therefor, provided with circular disks or head-flanges near one end; arms pivoted between the head-flanges; centering-jaws operating beyond said head-flanges and connected with said arms; and a ring rotatably supported upon the head-flanges, and provided with slots in which said arms are engaged. 95

2. The combination with a centering-punch; of a guide therefor; a set of centering-jaws connected with the guide; a jaw-adjusting ring having guide-slots, and operatively connected with the jaw; and a spring arranged 100

to actuate said ring to close the jaws upon the axial line of the punch.

3. The combination of a centering-punch and tubular guide therefor, provided with 5 head-flanges near one end; arms extending between said head-flanges, and pivotally secured thereto; centering-jaws connected with said arms; a jaw-adjusting ring rotatably mounted on said head-flanges, and provided 10 with diagonal guide-slots, in which the jaw-arms are engaged.

4. The combination of a centering-punch and tubular guide therefor, provided with head-flanges near one end; arms extending 15 between said head-flanges, and pivotally secured thereto; centering-jaws connected with said arms; a jaw-adjusting ring rotatably mounted on said head-flanges, and provided 20 with diagonal guide-slots, in which the jaw-arms are engaged, said jaws extending in the direction of ring rotation at an angle to the jaw-arms.

5. The combination of a tubular guide; a centering-punch mounted for limited longitudinal movement therein; a set of centering- 25

jaws, pivotally connected with the guide; and a spring adapted to hold said ring normally in position with the jaws in contact in the axial line of the punch.

6. The combination of a tubular guide, provided with circular head-flanges at one end; centering-jaws having arms pivotally secured between said head-flanges; an adjusting-ring having open-ended guide-slots adapted to receive said arms; a holder-sleeve rigidly connected with the guide; a punch mounted for longitudinal movement in the guide; said holder-sleeve and head-flanges forming annular bearings for the adjusting-ring; and a spring connected with the guide and adjusting-ring, and adapted to maintain the latter normally in a position with the jaws centered in the axial line of the punch. 30 35 40

In testimony whereof we affix our signatures in the presence of two witnesses.
